UNITED STATES PATENT OFFICE.

BENJAMIN F. HENDRICKS AND ELLSWORTH THOMPSON, OF QUINCY,
ILLINOIS.

FIRE-ESCAPE.

SPECIFICATION forming part of Letters Patent No. 702,858, dated June 17, 1902.

Application filed November 2, 1901. Serial No. 80,923. (No model.)

To all whom it may concern:

Be it known that we, BENJAMIN F. HENDRICKS and ELLSWORTH THOMPSON, citizens of the United States, residing at Quincy, in the 5 county of Adams and State of Illinois, have invented a new and useful Fire-Escape, of which the following is a specification.

This invention relates generally to fire-escapes, and more particularly to that class 10 known as portable "friction" fire-escapes, in which a friction device slides upon an escape-rope, the operator being suspended by means of a suitable harness attached to the friction device.

15 The object of this invention is to provide a fire-escape embodying the above-mentioned characteristics which shall be simple, durable, and highly efficient.

With these objects in view the invention 20 consists in the peculiar construction of the several parts and in their novel combination or arrangement, all of which will be fully described hereinafter and pointed out in the claims.

25 In the drawings forming part of this specification, Figure 1 is a perspective view illustrating the practical application of our invention. Fig. 2 is a perspective view of the friction device and harness. Fig. 3 is a side elevation of a portion of the friction device, the face-plate being removed. Fig. 4 is a section on the line 4 4 of Fig. 3. Fig. 5 is a section on the line 5 5 of Fig. 4. Fig. 6 is a detail perspective view of one of the bearing-plates. 30 Fig. 7 is a perspective view of one of the brake-blocks. Fig. 8 is a detail view of one of the friction-drums.

In carrying out our invention we employ a 35 metallic block A, which is formed with an opening A' adjacent to its upper end, and located in the said opening at each side are the bearing-frames B, slotted longitudinally, as shown at B', and journaled in the said slotted frames are the friction-drums C, the journals C' turning in the slots B' of the frames B, while the ends C² are provided with intermeshing pinions D, and the axle of one of the friction-drums is extended beyond the block and provided with suitable crank E.

45 45 The rope F, which is made fast at its upper end, passes centrally through the block, a ver-

tical bore G extending entirely through the block for said purpose. A rope F passes between the friction-drums, which are corrugated, as shown, and in order to forcibly hold 55 the said drums against the rope we employ the brake-blocks H, which are arranged within the opening A' and slide in the slotted frames, the ends H' bearing against the journals C' of the friction-drums, and regulating- 60 screws I are passed through the ends of the casing and bear against the brake-blocks for the purpose of regulating the tension upon the rope. The face-plates J are screwed upon the front and rear face of the block for the purpose of holding the mechanism in its proper 65 position. Supporting-ropes K are attached to the bottom of the block A and terminate in loops K', and the belt L is attached to the said supporting-ropes intermediate its ends. The 70 ropes K can be made any length desired, and the loops K' can serve as straps for the operator to stand in, or the loops can be used to support the body by passing the legs therethrough and fastening the strap around the waist, as 75 most clearly shown in Fig. 1. The crank-handle is then grasped in the right hand and the descent can be regulated by the operator, and in case it is desired to increase or decrease the friction it can be done by turning 80 the regulating-screw I in or out. By employing two regulating-screws the device is susceptible of use by either a right or left handed person. By having the friction-drums corrugated all danger of the ropes slipping is 85 avoided, and by having intermeshing gears or pinions upon both ends of both friction-drums the operation of the said drums is equalized and made uniform. It will thus be seen that we provide an exceedingly simple and efficient construction of portable 90 friction fire-escape.

Having thus fully described our invention, what we claim as new, and desire to secure by Letters Patent, is—

95 1. A fire-escape comprising in combination a block having an opening therein, friction-drums arranged in said opening, brake-blocks bearing against the journals of the said friction-drums, regulating-screws bearing against 100 the said friction-drums, the intermeshing gears connected to the friction-drums, and

an operating-handle connected to one of the said drums, substantially as described.

2. A fire-escape of the kind described, comprising in combination a block having an opening produced therein, bearing - frames arranged in the said opening, friction-drums journaled in the said bearing - frames, the brake-blocks and regulating-screws, the intermeshing gears attached to the friction- 5 drums, the operating - handle and the supporting-harness attached to the block, substantially as described.

3. A fire-escape of the kind described, a block having an opening therein, and a vertical bore traversing the said opening, the slotted bearing-frames arranged in the said 10 opening in the block, the friction - drums

journaled in the said bearing - frame, the brake-blocks sliding in the said frames and bearing upon the journals of the friction- 20 drums, the regulating-screws passing through the ends of the block and bearing against the ends of the friction-blocks, the intermeshing gears mounted upon the ends of the friction-drums, the operating crank-handle 25 attached to one of the friction-drums, the supporting-harness and face-plates, all arranged to operate as shown and described.

BENJAMIN F. HENDRICKS.
ELLSWORTH THOMPSON.
